UNITED STATES PATENT OFFICE.

ALBERT J. HORTON, OF WHITE PLAINS, NEW YORK, ASSIGNOR TO THE CUTLER-HAMMER MFG. CO., OF MILWAUKEE, WISCONSIN, A CORPORATION OF WISCONSIN.

ELECTRIC SWITCH.

993,526.

Specification of Letters Patent. Patented May 30, 1911.

Application filed September 14, 1908. Serial No. 452,882.

To all whom it may concern:

Be it known that I, ALBERT J. HORTON, a citizen of the United States, residing at White Plains, in the county of Westchester and State of New York, have invented new and useful Improvements in Electric Switches, of which the following is a full, clear, concise, and exact description, reference being had to the accompanying drawing, forming a part of this specification.

My invention relates to improvements in electric switches and has for its object to provide a switch for breaking circuit quickly.

According to the preferred form of my invention, I provide a movable contact adapted to be engaged by the switch and moved therewith when the same is moved to open position, said movable contact being arranged to fly out of engagement with said switch upon reaching a certain position.

For the purpose of more fully disclosing the characteristic features of my invention I have illustrated in the accompanying drawings a rheostat embodying one form thereof.

Of course, my invention may be used in various relations and it should be understood that the same is susceptible of various modifications.

In the accompanying drawings—Figure 1 is a front elevation of the rheostat. Fig. 2 is a top plan view of a portion thereof. Figs. 3 and 4 are detailed views of parts of Fig. 1, and Fig. 5 diagrammatically illustrates one circuit arrangement for this device.

The rheostat which I have shown is of a conventional type, the several parts thereof being preferably mounted on an insulating panel 1. Fulcrumed on a pin 2, protruding from the panel, is a controlling arm 3 which is provided with an operating handle 4. The arm 3 is adapted to be moved over a series of contacts 5. A coil spring 6 mounted on the pin 2 tends to move the arm 3 to the left against a stop 7 carried by the panel. The arm 3 carries an armature 8 which is adapted to engage the pole pieces 9 of the retaining magnet 10 when said arm is in its extreme right-hand position. The retaining magnet 10 is preferably of the low-voltage type and holds the arm 3 in its final posi-

tion. When the arm is released by the retaining magnet, the same returns to the position shown in Fig. 1, under the influence of 55 the spring 6.

Extending through the upper left-hand corner of the panel 1 and projecting from opposite sides thereof, is a rod 11. Secured to the rod 11 is a collar 12 which bears 60 against the face of the panel. Fulcrumed to the forward end of the rod 11 is a lever 13. A coil spring 14 surrounding the rod 11, has one end secured thereto and its opposite end secured to the lever 13. This spring tends 65 to move the lever 13 upwardly against a stop 15 projecting from the panel 1. The lever 13 is preferably of the shape shown and is provided at its end with an elongated portion 16. The lever 13 forms a movable contact, the function of which will be herein- 70 after explained.

Adjacent to its end, the arm 3 carries a roller 17 which is adapted to engage the lower edge of the portion 16 of the lever 13 75 when the arm is moved to the right, as shown by dotted lines, Fig. 1. The roller 17 is secured to the arm 3 by a bolt 18.

Mounted upon the rearwardly extending portion of the rod 11 is an electromagnet 19, 80 said rod forming the core thereof. Secured to the rod 11 by a screw 20 and depending therefrom, is a metallic plate or strip 21. The lower end of the strip 21 is connected to the fulcrum of the arm 3 by another metal- 85 lic strip 22. The strips 21 and 22, together with the movable contact 13 and the arm 3, when in the position shown in dotted lines, form a complete magnetic circuit for the magnet 19. As will be hereinafter explained, 90 the rod 11 forms part of the motor circuit, and in practice, I prefer to electrically connect the strip 21 to said rod and provide said strip with a binding-post 23, while I insulate the strip 21 from the strip 22. The 95 manner of insulating said strips from one another is best illustrated in Fig. 4. Interposed between the ends of the strips 21 and 22 is an insulating washer 24. The orifice in the strip 21 is provided with an insulating 100 bushing 25 which is provided at its end with an annular flange 26. The strips 21 and 22 are secured to the base by a bolt 27 provided at its end with a nut 28 which bears against

the insulating flange 26. By this arrangement the strips are effectively insulated from one another.

I shall now describe the circuit arrangement for this device shown in Fig. 5. The motor shown is of the compound type, being provided with an armature *a*, a series field winding *f* and a shunt-field winding *f'*. Current is supplied by the main lines 30 and 31. One terminal of the series field winding *f* is connected by conductor 33 through a switch 32 to main line 30. The opposite terminal of the series field winding is connected by conductor 34 to one terminal of the motor armature *a*. The opposite terminal of the armature is connected by conductors 35 and 36 to a binding-post 37 which is connected by conductor 38 with the last of the series of contacts 5. All but the first of the series of contacts 5 are connected to an armature resistance 39. The arm 3 is connected by conductor 40 to a binding-post 41 which is connected by conductor 42 through switch 32 to main line 31. One terminal of the retaining magnet 10 is connected by conductor 43 to the first of the series of contacts 5. The opposite terminal of said magnet is connected by conductor 44 to binding-post 45 which is connected by conductor 46 to one terminal of the shunt-field winding *f'*. The opposite terminal of the shunt-field winding is connected by conductor 47 to conductor 33. The first step of the armature resistance instead of being connected to the first of the contacts 5 is connected to the core of the magnet 19. One terminal of the magnet 19 is connected by conductor 50 to the first of the series of contacts 5, while the opposite terminal of said magnet is connected by conductor 51 to the resistance 39 at a point between the terminal thereof and the second of the series of contacts 5.

I shall now describe the operation of this device. Assuming that the arm 3 is in the position shown in Fig. 5, the motor circuit is open. If the arm 3 be moved to the right onto the first of the series of contacts 5, circuit will first be closed through the magnet 19 and the shunt-field winding *f'*. The circuit for the shunt-field winding may be traced from main line 31 by conductors 42 and 40 to the arm 3, thence to the first of the series of contacts 5, by conductor 43, through the retaining magnet 10, by conductors 44 and 46, through the shunt-field winding *f'*, by conductors 47 and 33 to main line 30. Circuit for the magnet 19 may be traced from the first of the series of contacts 5, by conductor 50, through said magnet, by conductor 51, through a portion of the first step of the resistance 39, and all of the remaining steps thereof, by conductors 38, 36 and 35, through the motor armature and series field winding *f*, by conductor 33 to main line 30. The motor circuit is thus closed

with practically all of the armature resistance 39 and the magnet 19 included herein. As soon as the magnet 19 becomes energized the portion 16 of the movable contact 13 is attracted to the roller 17 carried by the arm 3, thereby establishing a shunt-circuit around the magnet 19. Circuit may then be traced from the arm 3 by roller 17 to the movable contact 13, by the rod 11 and conductor 48, through all of the armature resistance 39, and thence through the motor armature and series field winding, as already traced. Inasmuch as a part of the first step of resistance 39 is included in the shunt-circuit around the magnet 19, said magnet will not be completely short-circuited, but will be maintained energized. As soon as the movable contact is attracted to the roller 17, carried by the arm 3, the magnetic circuit for the magnet 19 is completed, and hence the movable contact is held firmly against the roller 17 and insures a good contact. If now the arm 3 be released it will return to initial position under the influence of the spring 6. As soon as the arm 3 leaves the first contact 5, the circuit of the magnet 19 is opened. However, the deenergization of the magnet does not occur instantly and hence the movable contact 13 is held in engagement with the roller 17, carried by the arm 3, until after the arm has been moved off of the first contact 5. As long as the movable contact 13 is held in engagement with the roller 17 the motor circuit is maintained closed. As soon as the magnet becomes deenergized or as soon as the movable contact reaches such a position that the tension of the spring 12 overcomes the magnetic attraction between it and the roller, said movable contact will fly back to the initial position, thereby breaking the motor circuit with a snap. The arc thus formed upon the opening of the motor circuit is broken between the movable contact and the roller, thereby protecting the stationary contacts from damage. This arrangement is particularly advantageous where the controller handle is moved onto the first contact and then immediately returned to initial position for "teasing" or "jogging" the motor along. Such a manipulation of the controller handle will draw a heavy arc on the contact points due to the rush of current which passes through the rheostat when the circuit is first closed and before the armature speeds up. Such arcs would soon destroy the contacts unless the same were quickly stretched and broken. Assume now that instead of returning the arm 3 to initial position the same be moved onto the second of the series of contacts 5. The roller 17 is then disengaged from the movable contact 13 and then the motor circuit is completed from the arm 3 directly to the second of the series of contacts 5, and thence directly through the re-

- sistance 39 and through the motor armature and series field winding, as already traced. As soon as the arm leaves the first of the series of contacts the magnet 19 is short-circuited. Continued movement of the arm 3 to the right will gradually remove the resistance 39 from circuit and when the arm 3 reaches its final position the motor will operate at normal speed. The arm 3 is retained in its final position by the retaining magnet 10. If, from any cause, the magnet 10 releases the arm 3, said arm will return to its initial position under the influence of the spring 6.
- 15 In practice when the arm 3 flies back to initial position from the "full on" position under the influence of the spring 6, it usually moves at such a high rate of speed that the circuit of the magnet 19 is closed and opened so quickly that the movable contact 13 is not sufficiently magnetized to stick to the roller 17. However, the arc formed upon the opening of the motor circuit under these conditions is very small inasmuch as the motor is running at full speed and the C. E. M. F. generated thereby is approximately equal to the line voltage. Hence, the arc formed has little or no effect upon the contacts between which it is broken. Of course, if the arm moves back slowly from the "full on" position the movable contact would stick to the roller and the motor circuit would be broken in the manner already described.
- 20 Having thus described my invention, what I claim as new and desire to secure by Letters Patent is:
1. In combination, a switch, a movable contact adapted to be engaged by and moved with said switch, said contact being adapted to quickly disengage said switch upon continued movement thereof, and a stationary blowout coil for disrupting the arc formed upon said contact leaving said switch, the flux of said blow-out coil being concentrated at the point where contact is broken regardless of the location of said point. 100
  2. In combination, a switch, a movable contact adapted to be engaged by and moved with said switch, said contact being adapted to quickly disengage said switch upon continued movement thereof, and a blowout coil for disrupting the arc formed upon said contact leaving said switch, said contact forming part of the magnetic circuit of said blowout coil. 105
  3. In combination, a switch, a pivoted contact adapted to be engaged by and moved with said switch, means for causing said contact to quickly disengage said switch upon continued movement thereof and a blowout coil arranged substantially concentric with the axis of said pivoted contact, said contact forming one of the pole pieces of said blowout coil. 110
  4. In combination, a switch, a movable contact adapted to be magnetically held in engagement with said switch when the same is moved in one direction, and means for causing said contact to break engagement with said switch upon reaching a certain position. 70
  5. In combination, a pivoted switch, a pivoted contact adapted to be magnetically held in engagement with said switch when said switch is moved in one direction, and means for causing said contact to break engagement with said switch upon reaching a certain position. 75
  6. In combination, a switch, a movable contact arranged to be engaged thereby, an electromagnet for causing said contact to be held in engagement with said switch when said switch is moved in one direction, said contact being caused to break engagement with said switch upon reaching a certain position. 80
  7. In combination, a switch, a pivoted contact arranged to be engaged thereby, an electromagnet for causing said contact to be held in engagement with said switch when said switch is moved in one direction, and means for causing said contact to break engagement with said switch when said switch reaches a certain position. 90
  8. In combination, a switch, a stationary contact arranged to be engaged thereby, a movable contact arranged contiguous to said stationary contact and adapted to be magnetically attracted to said switch and held in engagement therewith when said switch is moved to open position, and means for causing said movable contact to break engagement with said switch after said switch is moved out of engagement with said stationary contact. 100
  9. In combination, a switch, a movable contact, an electromagnet having a core magnetically connected to said switch and to said contact, said magnet being adapted to cause said contact to be attracted to said switch and held in engagement therewith when said switch is moved to open position, and means for causing said contact to break engagement with said switch upon reaching a certain position. 110
  10. In combination, a switch, a stationary contact arranged to be engaged thereby to complete an electric circuit, a movable contact arranged contiguous to said stationary contact and adapted to be engaged by said switch and moved therewith when said switch is moved to open position, said switch and said movable contact being adapted to maintain the circuit closed after the former has been disengaged from said stationary contact, means for causing said movable contact to break engagement with said switch upon reaching a certain position and a stationary blowout magnet for 115
  - 120
  - 125
  - 130

disrupting the arc formed upon separation of said contact from said switch, the flux of said blow-out coil being concentrated at the point where contact is broken regardless 5 of the location of said point.

11. In combination, a pivoted switch, a stationary contact arranged to be engaged thereby to complete an electric circuit, a pivoted contact arranged contiguous to said stationary contact and adapted to be engaged by said switch and moved therewith when the same is moved to open position, said switch and said pivoted contact being adapted to maintain the circuit closed after the 10 former has left said stationary contact, means for causing said pivoted contact to break engagement with said switch upon reaching a certain position and a blowout coil arranged substantially concentric with 15 the axis of said pivoted contact, said pivoted contact forming a pole piece for said magnet.

12. In combination, a switch, a stationary contact arranged to be engaged thereby to 20 complete an electric circuit, a movable contact arranged contiguous to said stationary contact and adapted to be magnetically held in engagement with said switch to maintain the circuit closed after said switch is disengaged from said stationary contact, and means for causing said movable contact to move out of engagement with said switch upon reaching a certain position.

13. In combination, a switch, a stationary contact arranged to be engaged thereby to 25 complete an electric circuit, a movable contact arranged contiguous to said stationary contact, an electromagnet for causing said movable contact to be attracted to said switch and held in engagement therewith when said switch is moved in one direction to maintain the circuit closed after said switch is disengaged from said stationary contact, and means for causing said movable 30 contact to break engagement with said switch when said switch has reached a certain position.

14. In combination, a switch, a stationary contact arranged to be engaged thereby, a movable contact arranged contiguous to said stationary contact, an electromagnet adapted to be energized while said switch engages said stationary contact, said magnet having its core magnetically connected to said 35 switch and said movable contact for causing said movable contact to be magnetically attracted to said switch and held in engagement therewith when the same is moved to open position, and means for causing said 40 movable contact to break engagement with said switch after said switch has been disengaged from said stationary contact.

15. In combination, a series of stationary contacts, a resistance connected thereto, a 45 switch movable over said contacts for con-

trolling said resistance, a movable contact connected to said resistance and arranged contiguous to the first of said series of stationary contacts, said movable contact being adapted to be engaged by said switch before 50 said switch leaves said stationary contacts and to be moved therewith, and means for causing said movable contact to break engagement with said switch after said switch has been moved off of said stationary contacts.

16. In combination, a series of stationary contacts, a resistance connected thereto, a pivoted switch movable over said contacts for controlling said resistance, a pivoted contact connected to said resistance and arranged contiguous to the first of said series of contacts, said pivoted contact being adapted to be engaged by said switch before 55 said switch leaves said stationary contacts and to move therewith, and means for causing said pivoted switch to break engagement with said switch after said switch has been moved off of said stationary contacts.

17. In combination, a series of stationary contacts, a resistance connected thereto, a switch movable over said contacts for controlling said resistance, a movable contact connected to said resistance and arranged contiguous to the first of said series of contacts, said movable contact being adapted to be magnetically attracted to said switch when the same is moved onto the first of said series of stationary contacts and to be held in engagement with said switch when 100 said switch is moved in one direction, and means for causing said movable contact to break engagement with said switch when said switch has reached a certain position.

18. In a controller for electric motors, in combination, a series of stationary contacts, a resistance connected thereto, a switch movable over said contacts for controlling said resistance, a movable contact arranged contiguous to the first of said series of contacts 110 and connected to said resistance, an electromagnet having its core magnetically connected to said switch and said movable contact and for causing said movable contact to be attracted to said switch when the same is moved onto the first of said series of contacts and to be held in engagement with said switch when said switch is returned to initial position, and means for causing said movable contact to break engagement with 115 said switch when said switch has reached a certain position.

19. In a controller for electric motors, in combination, a series of stationary contacts, a resistance connected thereto, a switch movable over said contacts for controlling said resistance, a pivoted contact arranged contiguous to the first of said series of contacts 125 and connected to said resistance, an electromagnet connected in circuit between the 130

- first of said series of contacts and said resistance, said switch and said pivoted contact, when in engagement, being adapted to establish a shunt-circuit around said magnet, 5 said magnet having its core connected to said switch and said pivoted contact to cause said pivoted contact to be magnetically attracted to said switch when in engagement with the first of said series of contacts and 10 to be held in engagement with said switch when returned to initial position, and means for causing said pivoted contact to break engagement with said switch upon reaching a predetermined position.
- 15 20. In a controller for electric motors, in combination, a series of stationary contacts, a resistance connected thereto, a switch movable over said contacts for controlling said resistance, a pivoted contact arranged contiguous to the first of said series of contacts 20 and connected to said resistance, an electromagnet connected in circuit between the first of said series of contacts and said resistance, said switch and said pivoted contact, 25 when in engagement, being adapted to establish a shunt-circuit around said magnet, said magnet having its core connected to said switch and said pivoted contact to
- cause said pivoted contact to be magnetically attracted to said switch when in engagement with the first of said series of contacts and to be held in engagement with said switch when returned to initial position, means for causing said pivoted contact to break engagement with said switch upon 30 reaching a certain position, means tending to return said switch to initial position, and a retaining magnet for holding said switch in its final position.
21. In combination, a pivoted switch, a 40 relatively stationary pivoted contact coöperating with said switch to maintain circuit closed through said switch after the same leaves its stationary contact, a spring tending to withdraw said pivoted contact from said switch, means overcoming the tension of said spring for a temporary period and a blowout coil for disrupting the arc produced by said switch.
- 45 In witness whereof, I have hereunto subscribed my name in the presence of two witnesses.

ALBERT J. HORTON.
